(57) **CLAIM**

The ornamental design for a folding bicycle, as shown and described.

DESCRIPTION

FIG. 1 is a perspective view of the present invention in the unfolded position;

FIG. 2 is a side view illustrating the present invention in the folded position;

FIG. 3 is a top view illustrating the present invention in the unfolded position;

FIG. 4 is a bottom view illustrating the present invention in the unfolded position;

FIG. 5 is a right side view illustrating the present invention in the unfolded position;

FIG. 6 is a left side view illustrating the present invention in the unfolded position;

FIG. 7 is a front view illustrating the present invention in the unfolded position; and,

FIG. 8 is a rear view illustrating the present invention in the unfolded position.
